HEEL ATTACHING MACHINES

Paul E. Morgan, Melrose, and Willard L. Baker, Ipswich, Mass., assignors to United Shoe Machinery Corporation, Flemington, N.J., a corporation of New Jersey Continuation of abandoned application Ser. No. 23,625, May 12, 1960. This application May 8, 1961, Ser. No. 110,298

38 Claims. (Cl. 1—102)

This invention relates to heel attaching machines and is illustrated as embodied in a machine for attaching rubber heels and their associated base lifts to shoes by what is commonly known as "outside" nailing. This application is a continuation of our copending application for United States Letters Patent Serial No. 28,625, filed May 12, 1960, now abandoned.

In the use of conventional machines for attaching heels to shoes mounted on geometrically graded lasts, which are made of wood and have steel positioning plates secured to their back cones and which are disclosed in United States Letters Patent No. 2,806,233, granted September 17, 1957 on an application filed in the names of Arthur R. Hubbard et al. it has been found that heavy pressure applied heightwise to the last by the pushing action of the drivers of said machines has a tendency to force the positioning plate into the last or otherwise to displace said plate with relation to the wood last and often to crack the last.

Furthermore, in conventional heel attaching machines the last upon which the shoe is mounted is placed on a spindle of the jack and is moved rearwardly together with the jack by hand against a back gage. At the same time the right and left shoes mounted on right and left lasts are usually manually oriented by "eye" on the spindle of the jack posts so as to swing the vertical median plane of the heel seat of the last into register with a fixed reference plane of the jack and of the operating instrumentalities of the machine. Heel lifts and associated base lifts to be attached to shoes by conventional machines are placed in interchangeable heel forms which are moved into positions in which the heel lifts therein have their peripheries in opposed register with but lying slightly outside the feather lines of the heel seats of the shoes which have been mounted on the jack and are manually held by the operator during the heel attaching operation, the jack thereafter being moved by power toward the heel to force the heel seat of the shoe mounted on the jack against said heel preparatory to driving nails into the work. Machines such as above referred to require the services of a skilled operator since the shoe carried by the last must be moved together with the last against the back gage and must be oriented on the spindle of the jack by the operator in accordance with whether the shoe is a right or a left. Moreover, this operation is tiring on the operator.

It is an object of the present invention to provide an improved heel attaching machine which is simple in construction and by the use of which shoes mounted on geometrically graded last, for example, may have heels attached to them quickly and effectively by an unskilled operator without danger of damaging the last. It is another object of the invention to provide a heel attaching machine provided with means for automatically delivering heels to a position in which they are attached to the shoe.

With the above objects in view, the illustrative machine, which comprises a nailing die, a support for a last carrying a shoe, and means for effecting relative movement between the support and the jack to cause the heel and the heel seat of the shoe to be forced together, in accordance with a feature of the invention is provided with means for

2

driving nails into the heel and the heel seat of the shoe with impact action to attach the heel to the shoe.

With a view to reducing to a minimum the pressure applied against the work, and especially against the last during the attachment of the heel to the shoe, the jack of the illustrative machine, in accordance with another feature of the invention, is yieldingly supported, for example, by a "heavy" spring. The combination of a yieldingly mounted jack and driving of nails by impact action has resulted in materially reducing the pressure applied against the last during the heel attaching operation and has also resulted in providing a machine which is simple in construction and effective in its operation.

As above explained, in heel attaching machines now in use, the shoe carried by the last mounted on the spindle of the jack post is positioned lengthwise in the machine by moving the rear end of the counter portion of the shoe into engagement with the back gage, the orienting of the shoe on the spindle of the jack post to insure that the vertical median plane of the heel seats of right and left shoes shall be coincident with the reference plane of the machine being effected manually by the operator. In the present machine the last upon which the shoe is mounted is placed on a spindle which is constrained for movement in a rectilinear path extending lengthwise of the axis of the spindle and toward and away from the nailing die of the machine, but is not movable at right angles to this path as are the jack spindles of the conventional machines such as above referred to. The rear ends of the heel seats of geometrically graded lasts of different sizes are spaced graded distances from the axis of the thimble of the last, which axis lies in the vertical median plane of the heel seat of the last. It will thus be clear that since the axis of the spindle of the present jack is movable only lengthwise of its axis, the rear ends of shoes of different sizes operated upon by the present machine are arranged in different positions forwardly and rearwardly of the machine.

As above stated, the geometrically graded last has secured to the upper surface of its back cone a positioning plate, such as disclosed in said Patent No. 2,806,233. The present jack post is provided with abutments which, when the last carrying the shoe is placed upon the spindle, cooperate with the positioning plate of the last to orient the shoe on the jack so that the vertical median plane of the heel seats of right and left shoes will be arranged in the fixed reference plane of the machine.

The present machine, in accordance with further features of the invention, is provided with a heel carrier unit for automatically positioning and clamping heels of different sizes with their vertical or heightwise median planes arranged in a fixed reference plane of the carrier unit and with their axes of symmetry, which are herein-after defined and are included in said reference plane, lying in or coincident with a fixed axis of the carrier unit, said unit being automatically moved to a predetermined position in which the heel positioned and clamped in said unit is moved adjacent to the nailing die with the vertical median plane of the heel lying in the reference plane of the machine and the axis of symmetry of the heel arranged parallel to and adjacent to the axis of the spindle of the last, the distance between the spindle axis and the axis of symmetry of the heel positioned in the machine being constant, irrespective of the size of the heel. With such a construction it will be apparent that when the jack, and accordingly the shoe mounted on it, is moved in a rectilinear path toward the nailing die, and the heel seat of the shoe is forced against the heel and the heel is forced against the nailing die by the action of the jack post, a projection of the outline of the heel on the plane of the feather line of the heel seat of the shoe will lie a desired uniform distance outside said

feather line, and accordingly the heel, when attached to the shoe, will be correctly positioned on said shoe.

The heel carrier unit of the present machine has associated with it a magazine for supplying to it heels which comprise heel and base lifts. It will later be apparent that in order to attach a heel to a shoe an operator of the present machine only has to place the shoe on the spindle of the jack and to cause the shoulders of the positioning plate of the last to be brought into register with abutments on the jack. The heel is "dropped" automatically onto a table from the magazine at the end portion of the power cycle of the machine and, after the shoe has been placed on the jack, clamps forming part of the carrier unit position the heel automatically in the clamping unit with the vertical median plane of the heel coincident with the fixed uniform plane of the unit with the axis of symmetry of the heel arranged in a fixed axis of the carrier unit irrespective of the size of the heel, said carrier unit then being automatically swung to its heel attaching position beneath the nailing die during the cycle of the machine.

The present machine requires little, if any skill on the part of the operator and very little effort. The automatic heel delivery mechanism above referred to is relied upon to provide a fully automatic heel attaching machine disclosed in United States Letters Patent No. 3,048,862, granted August 14, 1962 on an application filed in the names of Dorosz et al.

The present invention consists in the above features and in other novel features which are hereinafter described and some of which are embodied in an improved nailing die, and an improved nail distributor, reference being had to the accompanying drawings, which illustrate one embodiment of the same, selected for purposes of illustration, said invention being fully disclosed in the following description and claims.

In the drawings:

FIG. 1 is a side elevation, partly broken away, of the illustrative machine;

FIG. 2 is a front view, partly broken away and partly in section, of nail driving mechanism of the machine;

FIG. 3 is a plan view, partly on the line III—III of FIG. 2, showing a nailing die of the nail driving mechanism and also showing in a loading position a carrier unit which is adapted to position and to clamp a heel, which comprises a heel lift and a base lift, and to transfer said heel to a heel attaching position beneath the nailing die and above the jack of the machine;

FIG. 4 is a section on the line IV—IV of FIG. 2 showing details of the nailing die and a gun for operating drivers which travel in nail tubes of said die, to drive nails into a heel, which is forced against the bottom of the nailing die, and into a heel seat of a shoe forced against said heel;

FIG. 5 is a section, partly on the line V—V of FIG. 2, showing details of the jack in its raised position with work mounted on it;

FIG. 6 is a section on the line VI—VI of FIG. 5 showing the upper end of a back cone of a geometrically graded last and lugs of the jack cooperating with a positioning plate on the last for positioning lasts and accordingly shoes on the jack;

FIG. 7 is a perspective view of a shoe to which the heel has been attached by the illustrative machine, the outline of the outsole and the heel of the finished shoe being shown in dash outline;

FIG. 8 is a view, partly in plan and partly in section on the line VIII—VIII of FIG. 4 showing details of the nail tubes of the nailing die and of mechanism for moving the tubes into different adjusted positions to vary the nailing patterns of said tubes in accordance with the size of the shoe being operated upon;

FIG. 9 is a section on the line IX—IX of FIG. 8;

FIG. 10 is a plan view of the carrier unit, the cover of which has been broken away, showing a heel lift

and its assembled base lift positioned and clamped in said unit ready to be swung to a heel attaching position beneath the nailing die;

FIG. 11 is a section on the line XI—XI of FIG. 10;

FIG. 12 is a side elevation, partly in section, illustrating a nail distributor of the machine;

FIG. 13 is a section on the line XIII—XIII of FIG. 15;

FIG. 14 shows a portion of the front of the nail distributor;

FIG. 15 is a plan view, partly broken away of the nail distributor;

FIGS. 16 and 17 combined is a schematic view of fluid pressure operated mechanism of the machine and is especially useful in describing the operation of the machine;

FIG. 18 is a plan view of a magazine which is mounted above the carrier unit of the machine and is adapted automatically to feed heel lifts and their associated base lifts to the carrier unit;

FIG. 19 is a front view, partly broken away, of the magazine and a portion of the carrier unit shown in FIG. 18;

FIG. 20 is a view showing the bottoms of right and left geometrically graded lasts superimposed on each other and illustrating that the heel end portions of the lasts are coincident and that the toe ends of the lasts are laterally offset from each other;

FIG. 21 is an illustrative view used in describing the characteristics of a conventional heel or heel lift attached to shoes by the use of the illustrative machine; and

FIG. 22 shows a portion of the fluid pressure diagram with a reset valve incorporated therein.

The illustrative machine is described with reference to attaching a composite heel 30, which comprises a rubber lift 32 and a base lift 34, to a heel seat 36 (FIG. 7) of a shoe 38 and comprises a jack 40 (FIGS. 1, 2 and 5) for supporting upside down a geometrically graded last 42 in which the shoe is mounted, a multipart nailing die 44, a nail driving gun 46, a nail distributor 48 for supplying nails 49 to the nailing die, a magazine 50 from which the heels are successively delivered to a stable 52, and a carrier unit 54 which is adapted successively to position and to clamp the heels resting on the table and to move them from said table to a heel attaching position just below the nailing die. The heel lift 32 per se may be regarded as a heel and if desirable the machine may accommodate rubber heels having base lifts "spotted" to them.

When the shoe 38 has been positioned upon the jack 40 and the heel 30 has been placed upon the table 52 the machine operates automatically through its cycle causing in succession, through fluid (pneumatic) pressure operated means hereinafter disclosed, the carrier unit 54 to clamp the heel, which has been manually placed upon the table 52 or has been "dropped" automatically onto the table from the magazine 50, and thereafter to move the clamped heel to a predetermined heel attaching position below the nailing die 44, the jack 40 to be raised to force the heel seat 46 of the shoe 38 against the heel 30 and the heel against the lower ends of lateral nail tubes 56 and front and rear nail tubes 56a of the nailing die, and the gun 46 to be operated to drive, by multi-impact action nails 49, which have been delivered to the nailing die 44 and have their pointed ends resting in recesses 58 (FIGS. 7 and 10) in the tread face of the heel, into the heel and the heel seat of the shoe, said nails being clinched in said heel seat by reason of their being forced against a heel plate 60 of the last 42 during the final part of the driving operation whereby to attach the heel to the shoe.

When the heel 30 has been attached to the shoe 38 it is released from the carrier unit 54, the jack 40 and the gun 46 are moved to their lowered and raised starting or retracted positions respectively, and the carrier unit 54 is moved back to its loading position over the table

52 and beneath the heel magazine 50, the lowermost heel in the magazine falling by gravity onto the table.

The machine comprises a base 62 and a vertical column 64 bolted to said base. Bolted to the column 64 is a bracket 66 having secured to it a pair of vertical guide rods 68 serving to guide the gun 46 vertically toward and away from the nailing die 44 which is supported on a bracket 70 bolted to the column. The column also has bolted to it a bracket 72 (FIGS. 1 and 5) which supports the jack 40 and operating means therefor.

Formed in a table portion 74 of the bracket 72 is a rectilinear slot 76 and mounted in said slot is a supporting plate 78 which has welded to it a bearing post 80 and may be initially adjusted lengthwise of said slot and forward and rearward of the machine by turning a thumb screw 82 threaded into the plate and rotatably mounted on a lug 84 secured to the table portion of the bracket. The plate 78 may be clamped in its initial setting in the slot 76 formed in the table portion 74 of the bracket 72 by the use of screws 86 which pass through a recess 88 in said table portion and are threaded into a ring-shaped block 90.

Vertically slidable in the bearing post 80 is a piston rod 91 which has formed in its upper end a bore 92 for receiving a shank portion 94 of a jack post 96 having secured to it an arm 98 which fits in a spline-way 100 formed in the piston rod and insures against rotation of the post upon said rod. Interposed between a face of the jack post 96 and the upper end of the piston rod 91 are spring washers 102 which are disclosed in United States Letters Patent No. 65,790, granted June 18, 1867 on an application filed in the name of Julien F. Belleville and constitute strong resilient means or springs for constantly urging the jack post in its rest position upwardly on the piston rod 91 until the arm 98 engages a shoulder 104 of said rod. The jack post 96 has an upstanding spindle 106, which is adapted to receive a thimble 108 (FIGS. 6 and 29) of the geometrically graded last 42 carrying the shoe 38, said last having at its back cone a flat upper face 110 adapted to be engaged by a positioning plate 112 of the last.

40 The geometrically graded last 42 is disclosed in United States Letters Patent 1,948,547, granted February 27, 1934 on an application filed in the name of Laurence E. Topham and comprises the above-mentioned thimble 108 which is centered about an axis 114 and a heel seat 118 formed by the heel plate 60 against which the heel attaching nails 49 are cinched. Lasts 42 of different sizes have the rear ends of their heel seats 118 spaced different distances from the axes 114 of the thimbles 108 of the lasts. Firmly secured to the upper face of the back cone of the last 42 is the positioning plate 112 which, as will be explained, is used to orient the last about the spindle 106 of the jack post 96, said plate having formed in it a hole which registers with the upper end of the thimble 108 of the last. The positioning plate 112 may be considered part of the last 42 and is disclosed in detail in Patent No. 2,806,233.

45 As explained in Patent No. 2,806,233, right and left geometrically graded lasts 42 have the center lines 120 (FIG. 20) of their foreparts, which center lines extend between the tip of the toe end of the bottom of the last and the axis 114 of the thimble 108, disposed at equal angles alpha at opposite sides of a vertical median plane 122 of the heel seat 118 of the last which plane includes a line extending from the rear end of the heel seat of the last to the axis of the thimble. The positioning plates 112 of right and left lasts 42 have front and rear pairs of parallel planar shoulders or faces 124, 126 (FIG. 6) respectively, the plates being secured to the upper faces of the back cones of the lasts with their front shoulders 124 arranged parallel to and spaced equal distances from the center lines 120 of the foreparts of the lasts and with their rear shoulders 126 arranged parallel to and spaced equal distances from the vertical median planes 122 of the

heel seats 118 of the lasts. It will be noted that the heel seats 118 of the right and left lasts 42 are substantially coincident while the toe ends of the lasts swing laterally away from each other.

5 The machine is provided to position right and left lasts 42, which carry the shoes 38, upon the spindle 106 of the jack post 96 with the vertical median planes 122 of the heel seats 118 of the lasts coincident with a fixed reference plane 128 (FIGS. 2 and 8) of the machine, which reference plane is also the vertical longitudinal median plane of the jack 40 and of the nailing die 44, the post 96 of the jack is provided with a pair of upstanding lugs 130 which are engaged respectively by the rear shoulders 126 of the positioning plate 112 of the last upon the jack post 15 spindle 106.

20 The bearing post 80 has welded to it an annular block 132 screwed to a cylinder 134 having reciprocable in it a piston 136 secured to the connecting rod 91. When the jack post 96 is in its lowered work receiving position a lower threaded end portion of the piston rod 91 is in engagement with the lower end of the cylinder 134.

25 The bracket 70, which is secured to the upstanding column 64 of the machine, has formed in it a pair of openings 138 (FIGS. 8 and 9) spaced by a central web and this web is provided with front and rear rectilinear guideways 140. The bracket 70 is provided with four threaded bores for receiving headed screws 142 which have spacers 144 (FIGS. 4 and 8) mounted on them and extend through bores in a cover or guide plate 146. The 30 bracket 70 also has threaded into it headed screws 141 which pass through bores in the cover plate 146 and have spacers 143 mounted on them, these screws cooperating with the screws 142 to secure the cover plate 146 in a predetermined fixed relation with the bracket 70. The cover plate 146 has formed in it openings 145 (FIG. 3) and guideways 147 which are similar to the openings 138 and the guideways 140 respectively formed in the bracket 70, said openings and guideways being arranged in vertical alignment. Extending vertically through the openings 138, 145 in the platform 70 and the cover 146 are the side or lateral nail tubes 56 and extending through the guideways 140, 147 are the front and rear tubes 56a, each of said tubes being provided with large and small bores or passages 148, 148a in which the drivers 150 respectively reciprocate. The lateral nail tubes 56 have formed integral with them angularly shaped carrier arms 152 fitting slidably between the guide or cover plate 146 and the upper face of the bracket 70, the front and rear tubes 56a having formed integral with them arms 153 which are rectangular in cross section and are also slidably between the guide or cover plate 146 and the upper face of said bracket. The large and small passages 148, 148a of the nail tubes 56, 56a may be collectively referred to as the passages of said tubes.

55 Formed in the under side of the guide or cover plate 146 are slots 154 the vertical median planes of which include a vertical central axis 156 of the nailing die 44, said axis being referred to as the central axis of the pattern or design of the tubes 56, 56a of said die. Rotatably in a circular rabbet 158 (FIGS. 4 and 9) of the bracket is a cam plate 160 having inner and outer cam ways 162, 164 (FIG. 8). The tube carrying arms 152, 153 have secured to them pins 166, 168 (FIGS. 4 and 8) the upper ends of which have rotatably mounted on them rolls 170, 172 fitting in the slots 154 formed in the cover plate 146. Rotatably mounted on the lower ends of the pins 166, 168 are rolls 174, 176 which engage in the inner cam ways 162. The angular carrier arms 152 also have secured, respectively, to them pins 178 having rotatably mounted on them rolls 180 which fit in the associated outer ways 164 of the cam 160. When the cam 160 is rotated the arms 153 and accordingly the front and rear nail tubes 56a move in rectilinear paths toward or away from the axis 156 of the nailing die 44 and the pins 166 in the angularly shaped carrier arms 152 move in rectilinear

paths toward and away from said axis and also serve as fulcrums about which the arms 152 are swung by movement of the associated rolls 180 along the outer grooves 164.

The cam 160 may be readily rotated into a desired operating position along the rabbet 158 of the bracket 70 by the provision of a rack 182 which is formed on the cam and meshes with a pinion 184 keyed to a pin 186 rotatably mounted in bores of the bracket and cover plate 146. Secured to the upper end of the pin 186 is a bevel gear 188 (FIG. 3) meshing with a bevel gear 190 which is fixed to a shaft 192 journaled in a bearing boss 194 secured to the cover plate 146. The cam ways 162, 164 of the cam 160 are so designed that the nail tubes 56, 56a may be set in any one of nine nailing designs readily determined by causing a selected one of a plurality of calibrated notches 196 formed in the periphery of the cam to be brought into register with a spring-pressed plunger 198 mounted on the bracket 70.

The nail tubes 56, 56a have formed in them bores 195 (FIGS. 4 and 9) which are of suitable diameter to receive the lower ends of plastic nail tubes 197. Nails are delivered to the upper ends of the nail tubes 197 at the proper time from the nail distributor 48 as will be hereinafter described.

The nail driving gun 46 has a threaded upper end onto which is screwed, a sleeve 200 (FIGS. 1, 2 and 4) having mounted on it a cover plate 202, an annular chamber 204 being formed between the sleeve, the cover plate and a threaded upper end portion of the gun. Arranged above the cover plate 202 are a pair of spaced washers 206 and interposed between said washers is a nut 208 having threaded into it the lower end portion of a rod 210 secured to a piston 212 reciprocable in a bore 214 of a vertically arranged cylinder 216 threaded into a platform 218 carried by the vertical guide rods 68. The sleeve 200, the cover plate 202 and a presser plate 220 have formed in them alined bores for receiving bolts 222, the presser plate being forced by nuts 224, which are threaded onto the upper ends of the bolts, against the upper washer 206 in order operatively to connect the piston rod 210 to the gun 46. The cover plate 202 has laterally extending flanges provided with bores for receiving bearings 225 which are slideable along the rods 68.

The gun comprises a barrel 226 having formed in it upper and lower bores 228, 230, in which an impact piston or block 232 and a hammer or jack set 234 respectively are reciprocable, said lower bore having a diameter slightly greater than the diameter of the upper bore.

Clamped by a plurality of bolt and nut connections 236 (FIG. 2) to the lower end of the barrel 226 of the gun 46 is a two part carrier block 238 which is provided with bores 240 for receiving respectively headed rods 242 to the lower ends of which a stripper or extractor plate 244 is secured by nuts 246. The rods 242 and accordingly the stripper plate 244 are constantly urged downward by springs 248 which surround the rods and are interposed between the carrier block 238 and the stripper plate 244, downward movement of said plate with relation to said block being limited by the engagement of the heads of the rods with transverse shoulders in the bores of the block. The carrier block 238 has laterally extending flanges provided with bearings 250 which are slidingly mounted on the guide rods 68. The carrier block 238 has secured to it one or more depending pins 252 which fit slidingly in vertical slots 254 respectively of the hammer or jack set 234 and insure against any displacement of said hammer about the common axis of the upper and lower bores 228, 230 of the gun 46.

The stripper plate 244 has formed in it eight slots 256 which converge generally toward and away from the axis of the bores 228, 230 and through which extend the drivers 150, said drivers having secured to the under sides of their heads nylon washers 258, which have diameters substantially greater than the widths of the slots, and ac-

cordingly bridge said slots. It will be noted that the drivers 150 have upper portions of relatively large diameter and lower portions of relatively small diameter adapted to fit slidingly in the large and small bores 143, 148a of the nail tubes 56, 56a the length of the lower portions of the drivers being such that before bottoming against converging walls formed between the bores 143, 148a they will project further below the bottoms of the associated nail tubes 56, 56a than is necessary to accommodate the thickest work to be penetrated.

High pressure air is delivered to the chamber 204 of the gun 46 by control means hereinafter described. The barrel 226 of the gun 46 has formed in it a pair of passages 262, 264 which lead from the chamber 204 of the gun to the upper bore 228 and also has a passage 266 extending from said bore to exhaust. Arranged in the chamber 204 in opposed relation to the outer ends of the passages 262, 264 is a floating annular valve 268 which operates alternately to open one passage 262, 264 to high pressure air from the chamber and to close the other passage from said chamber and vice-versa in the manner common to present percussively driven devices of the prior art such for example as disclosed in United States Letters Patent 2,911,645, granted November 10, 1959 on an application filed in the name of William P. Crossen.

When air under high and exhaust pressures is admitted to chambers 270, 272 formed respectively by the cylinder 216 and faces 274, 276 of the piston 212, the gun 46 guided by the rods 68 moves downward in a rectilinear path until the rear end of the carrier block 238 engages a plunger 278 of a pilot valve 280 supported by the bracket 66 thereby causing, through means hereinafter described, high pressure air to be available for the chamber 204 of the gun, this condition occurring when the gun has moved downward to a position in which the lower end of the barrel 226 of the gun substantially engages a conical upper face of the hammer 234, the lower face of the hammer at this time being in engagement with the heads of the nail drivers 150 shanks of which in turn are in engagement with nails 49 which rest in the lower passages 148a of the nail tubes 56, 56a with their pointed ends in the recesses 58 of the heel lift 32. It will be apparent that at the time air is admitted to the chamber 204 of the gun 46, the heads of the drivers 150 are spaced substantial distances above the stripper plate 244 so that, as the hammer 234 strikes the drivers 150, said drivers will be rendered effective to drive the nails into the work.

When pressure has been built up in the chamber 204 of the gun 46, the impact block 232 reciprocates rapidly in the bore 228 of the gun and strikes with repeated high speed blows or impact action against the hammer 234 causing the nails 49 then in the bores 148a of the nail tubes 56, 56a to be driven by the drivers 150 into the heel 30 and the heel seat 36 of the shoe 38 mounted on the jack 40, said nails being clinched against the heel plate 50 of the last 42 carrying the shoe as the gun follows the hammer downward as fast as permitted while the nails are being driven into the work.

The extent to which the nails 49 are driven into the work is controlled by the engagement of a cam plate 282, which is mounted on the carrier block 238, with a lever 283 which operates a plunger 284 of a differential pilot valve 286. Operation of a spool 288 of the differential pilot valve 286 from its full line position to its dash-line position (FIG. 17) as the result of bleeding air from a chamber 290 of this valve by the operation of the plunger 284 causes, by means hereinafter described, high pressure air to be cut off from the chamber 204 of the gun 46 with the result that reciprocation of the impact block 232 of said gun ceases and accordingly the driving of the nails 49 into the work also ceases, the gun during the completion of the cycle of the machine being elevated to its raised starting position by the piston rod 210 as will be explained later. The striker plate 282 has a shank portion 292 the upper end of which projects above the carrier

block 238 and has threaded onto it a nut 294. A spring 296, which surrounds the shank portion 292 of the cam plate 282 and has its upper and lower ends engaged respectively by the carrier block 238 and the plate 282, normally maintains the nut in engagement with the upper end of the carrier block. With the above construction it will be clear that the cam plate 282 will yieldingly engage the lever 283 and may have its operating position changed upon the carrier block 238 by the adjustment of the nut 294.

When the peripheral outlines or contours C, C' of any two of a run of sizes of conventional heels or heel lifts 32 in superimposed symmetrical relation are projected on a plane as shown in FIG. 21, the distances A between corresponding points on the side and rear portions of the contours are equal, the distances B between corresponding points on the breast portions of the contours being equal but slightly smaller than the distances A. The distances A and B between the outlines of heels of successive sizes are constant.

Distances D, D', which are equal to one-half the maximum widths of the contours C, C' and are measured from the rear ends of the contours along a common vertical median plane 386a of the contours, terminate at a common point E and an axis, which is disposed at right angles to the tread faces of heels represented by the contours and passes through this point, is known as an axis of symmetry of the heels. In other words, when the outlines C, C' of heels of different sizes are projected in symmetrical relation on a common plane, the vertical median planes 386a of the contours at that time being coincident, their points E, measured as above described, will coincide and an axis disposed at right angles to the plane and passing through the point E coincides with and is commonly referred to as the axis of symmetry of any one of the heels represented.

As above explained, the axes 114 of the thimbles 193 of geometrically graded lasts are located size-graded distances from the rear ends of the heel seats 118 of the lasts and preparatory to the attaching of heels to right and left shoes carried by these lasts, the shoes together with the lasts which carry them have to be swung about the axis of the spindle into positions in which the vertical median planes 122 of their heel seats 118 lie in the reference plane 128 of the machine.

The spindle 106 of the jack post 196 is moved only in a vertical rectilinear path extending lengthwise of the axis of said spindle and the shoe may be placed on the spindle and quickly and effectively oriented on the spindle to its proper position on the jack post by moving the rear shoulders 126 of the positioning plate 112 of the last into register with the lugs 130 of the post.

It may be explained at this point that after the heel lifts 32 and their top lifts 34 have been attached to the shoe they are trimmed along dash-lines as shown in FIG. 7, conventional trimming machines (not shown) utilizing the crease 317 between the outsole and the counter portion of the shoe along its feather or break line 319 to guide the work past the cutters of such machines. It will also be noted that in order not to have to provide a great number of heel lifts and base lifts of different sizes one size of heel lift and its associated base lift are commonly attached to more than one size of shoe with the result that during the heel trimming operation more material may be trimmed from the heel and outsole of one shoe than from the heel and outsole of another shoe. The rubber lift 32 which, when no base lift is used, may be referred to as a rubber heel usually has formed on its tread face designs of different types and if too much material is trimmed from the heel lift or the heel, the appearance of the tread face of the heel lift or heel will be spoiled. For this reason the amount of material that can be trimmed from the heel lift is limited while the amount that can be trimmed from the base lift is not critical. For this and other reasons in rubber heel work the base lift is commonly allowed to project slightly beyond the heel

lift. It may also be mentioned that it is desirable if possible to avoid having to trim the breasts of heel lifts 32 and their base lifts 34 because of various complications involved including the danger of damaging the shank portions of the outsoles of the shoes. Accordingly, as will be explained later, the similar breast faces of the heel lifts 32 and the base lifts 34 are aligned in the carrier unit 54 as will be hereinafter explained.

The heel carrier unit 54, which may also be referred to as a heel positioning and clamping unit, comprises a base plate 300 (FIGS. 3 and 10) secured to an arm 302 journaled on a bearing pin 304 mounted on a lug 306 secured to the vertical column 64, and a cover 308 secured by screws 310 to the base plate, said cover and base plate having formed in them vertically registering U-shaped openings 312, 312a which are adapted to receive heels and base lifts 32, 34 and when the machine is idle are arranged over the flat upper face of the fixed table 52 which is secured to a bracket 314 bolted to the column 64. As above explained, the heel and base lifts 32, 34 are placed upon the table 52 by hand or preferably are "dropped" automatically onto the table from the magazine 50.

The carrier unit 54 is rotated about the bearing pin 304 to move the heel and base lifts 32, 34 positioned and clamped in said unit from a work receiving station over the table 52, as shown in FIG. 10, to a heel attaching station just below the nailing die 44. Counterclockwise movement of the carrier unit 54, as viewed in FIG. 3, about the bearing pin 304 is limited by the engagement of the arm 302, upon which the carrier unit is mounted, with a stop screw 315 (FIG. 3) secured to the outer end of the lug 306.

Journaled on the base plate 300 is a cylinder 316 having a bore 318 in which is slidably a piston 320 having secured to it a rod 322 journaled to the left end (FIG. 10) of a lever 324 pivotally mounted on a bearing stud 326 secured to the base plate. Journaled on a bearing stud 328 secured to the base plate 300 is a lever 330 operatively connected to the lever 324 through a link 332. The levers 324 and 330 have pivotally connected to them links 334, 334a and extending between the links is a rear clamp or gage 336. The right end of the rear gage 336 has a circular opening 337a for receiving a stud 335a secured to the link 334a and the left end of the rear gage has secured to it a stud 335 which extends through an elongated slot 337 formed in the link 334, a spring-pressed plunger 339 slidable in the link 334 normally maintaining the stud in engagement with the forward end of the slot. When the clamp 336 is forced with substantial pressure against the rear end of the heel lift 32 it will pivot about the stud 335a against the action of the spring-pressed plunger 339.

The forward ends of the links 334, 334a are pivotally connected to levers 338 pivoted on bearing studs 340 secured to the base plate 300 and pivotally connected to these levers are right and left side clamps 342 which are pivotally connected to arms 344 journaled on bearing studs 346 secured to the base plate 300. The levers 338 are operatively connected by links 348 to T-shaped levers 350 journaled on bearing studs 352 secured to the base plate 300. Pivotally connected to the T-shaped levers 350 are slide clamps 354 which are pivotally connected to links 356 journaled on studs 358 secured to the base plate 300, the levers 350 also being operatively connected by links 360 to a breast clamp 362 having a convex face 364 complementary to and adapted to engage the breast faces of the heel and base lifts 32, 34.

The rear clamp 336 and the side clamps 342, 354 have secured to their inner or work-engaging portions depending pins 366 each of which carries a leaf spring 368 adapted to engage the base lift 34, which rests on the table 52, just before the associated rear and side clamps engage the heel lift, the leaf springs 368 yielding to insure that these springs shall not interfere with the

proper positioning of the heel lift in the carrier unit 54. If desirable the side clamps 354 may be yieldingly connected to their associated T-shaped levers 350. Accordingly each of the clamps 354 has formed in it a slot 370 through which passes a stud 372 secured to the associated T-shaped lever 350, and carried by each of the clamps 354 is a spring-pressed plunger 374 which normally retains the stud in engagement with the outer end of the slot.

As the piston rod 322 moves forward as the result of high pressure air being available for a face 378 of the piston 320 and a face 380 of the piston being open to exhaust, the front and rear clamps 362, 336 together with the side clamps 342, 354 and their associated leaf springs 368 move in converging paths to engage the work which consists of the heel lift 32 and its associated base lift 34 which may have been manually placed on the table 52 or automatically delivered to the table from the magazine 50. The breast clamp 362 and the side clamps 342 positively engage the heel lift 32 to move it on the table to its position shown in FIG. 10. The rear clamp 336 and the side clamps 354 which are yieldingly urged against the heel lift assist the breast clamps 362 and the side clamps 342 in the positioning of the heel lift. The lower portion of the breast clamp 362 (FIG. 19) and the associated leaf springs 368 of the rear clamp 336 and the side clamps 342, 354 cooperate to position the base lift 34 on the table to its position shown in FIG. 10.

The construction and arrangement of the side clamps 342 and the breast clamp 362 is such that they open and close at such a ratio that the conventional heel or heel lift clamped therein will always have its vertical median plane 386 coincident with a reference plane 375 of the carrier unit 54 and will always have its axis of symmetry coincident with a fixed vertical reference axis 384 of the carrier unit 54.

As above explained, the breast clamp 362 moves the breasts of the base lift 34 and the heel lift 32 into register, the base lift which is usually slightly larger than the heel lift projecting a substantially uniform distance beyond the side and rear faces of the heel lift. In view of the fact that the amount of material that can be removed from the base lift 34 during the heel trimming operation is not critical the leaf springs 368 are quite satisfactory in the positioning of the base lift in the carrier unit 54.

As above stated, the yieldable rear clamp 336 and the yieldable side clamps 354 may be given a slight lead in order that the heel lift 32 may be prepositioned before it is operated upon by the breast clamp 362 and the side clamps 342 which positively engage the heel lift. The carrier unit 54 may be described as having a fixed reference plane 375 which is spaced equidistant from the side clamps 342 and is normally spaced equidistant from the side clamps 354. When the heel lift 32 has been positioned and clamped in the carrier unit 54 its vertical median plane 386 may be described as lying in the reference plane 375 of said unit.

When the heel and base lifts 32, 34 on the table 52 have been positioned and clamped in the carrier unit 54, this unit is swung on the bearing pin 304 into a position in which the vertical median plane 386 of the heel and accordingly the reference plane 375 of the carrier unit coincide with the vertical reference plane 128 of the machine, this relation being controlled by the engagement of the arm 302 of the base plate 300 of the carrier unit 54, with a stop screw 388 threaded into the column 64 of the machine.

In order to effect swinging movement of the carrier unit 54 between its loading position shown in FIG. 3 and its heel attaching position below the nailing die 44, the arm 302 has pivotally mounted on it a cylinder 392 provided with a bore 394 in which a piston 396 is slideable. The piston 396 has secured to it a connecting rod 398 pivotally connected to a block 390 secured to the column 64 of the machine. High pressure air and air open to

exhaust is made available for chambers 400 and 402, which are formed respectively by the cylinder 392 and faces 404, 406 of the piston 396, alternately to cause the carrier unit 54 to be transferred from its loading position to its heel attaching position.

When the carrier 54 has been moved to its heel attaching position the axis of symmetry of the heel lift 32 lies in the reference plane 128 of the machine and will be parallel to and spaced slightly from the axis 114 of the thimble 108 of the last 42 positioned upon the spindle 106 of the jack post 96, the distance between the axis of symmetry of the heel lift and the axis of the thimble being constant irrespective of the size of the heel. It will thus be apparent that the carrier unit 54 is adapted automatically to locate heels of different sizes beneath the nailing die 44 in positions in which the vertical projections of the outlines of these heels on the planes of the feather lines respectively of the shoes carried by the last positioned on the jack, will lie a substantially constant distance outside said feather line and in "nested" relation.

As stated above, by using this method of positioning heels with relation to the shoe on the jack, the services of a skilled operator are no longer required in the attachment of the heel to the shoe. Moreover, the providing of carrier units 54 such as above described is an important step in the providing of the fully automatic heel attaching machine disclosed in said application Serial No. 28,801.

As will be explained later, in the fluid pressure control system of the machine the nail distributor 48 is operated in response to movement of the carrier unit 54 beneath the nailing die 44. Accordingly the arm 302 through which the carrier unit 54 is supported for pivotal movement has mounted on it a pilot valve 412 provided with a plunger 414 which as the carrier unit approaches its heel attaching position beneath the nailing die engages a screw 416 adjustably mounted on the column 64 whereby to cause the nail distributor 48 to operate.

The nail distributor 48 is mounted upon the upper end of the vertical column 64 and comprises a raceway 418 which is secured by screws 420 to the column and has formed in it a plurality of slots 422 which are inclined to the horizontal and are adapted to receive nails 49 with their heads overlying an upper face 424 of the raceway.

Pivotal mounted on trunnions 426 fitting in bores of bosses 428 (only one shown) of the column 64 is a nail hopper 430 which is provided with a generally flat floor 432 having formed in its slots 434 which, except for their lower ends, are of uniform width. The hopper 430 has the general appearance of an open top box and has upstanding side and end walls, portions of the floor along opposite sides of the rear portions of the slots 434 being cut way to form nail receiving depressions 436. A baffle plate 438 extends from one side wall of the hopper 430 to the other and is spaced from the floor 432. Extending downward from the bottom of the hopper 430 is a lug 440 which is pivotally connected to the upper end of a piston rod 442.

The hopper 430 has secured to it a solid ramp 444 which extends from the floor 432 of said hopper to the front wall of the hopper and from one side wall of the hopper to the other. Forward end portions of the slots 434 just rearward of the lower end of the ramp 444, which is almost flush with the floor 432, terminate in widened slot portions 434a, the construction and arrangement being such that the nails traveling down the slots 434 will drop through said widened slot portions into covered lower slots or passages 446 which are formed in a lower floor portion of the hopper beneath said ramp and are in effect continuations of the slots 434.

Opposing adjacent ends of the raceway 418 and the floor 432 of the hopper 430 are undercut as best shown

in FIGS. 12 and 13 and substantially engage each other along a common axis 450 of the trunnions 426. As the hopper 430 swings between its full line retracted position (FIG. 12) and its dash-line projected position nails in the hopper are shaken and drop into the slots 434 with their heads engaging the floor 432. During movement of the hopper 430 to its dash-line position (FIG. 12) the nails slide down the slots 434 and as they arrive at the ramp 440 they fall into the widened slot portions 434a and into the lower slots 446. The lower ends of the slots 446 of the hopper 430 are in register with the upper ends of the slots 422 formed in the raceway 418 and when the hopper is raised to its dash-line position nails in the slots 446 will be transferred to the registering slots 422 of the raceway 418.

The piston rod 442 which is pivotally connected to the lug 440 of the hopper 430 is secured to a piston 452 slideable in a bore of a cylinder 454 fulcrumed at its lower end to the column 64 of the machine. The cylinder 454 and a lower face 456 of the piston 452 form a chamber to which high pressure air is supplied, said piston being normally retained in a rest position at the lower end of the bore by a spring 460. The lug 440 of the hopper 430 is also operatively connected to a link 462 pivotally connected to an arm 464 pinned to a shaft 466 journaled in bearings 468 secured by screws to a block 470 which in turn is secured to the column 64 and also to the raceway 418. Also pinned to the shaft 466 is a thrust arm 472 the purpose of which will be explained later.

Secured by screws 474 and spacers to the block 470 is a front wall 476 having formed in its rear face a plurality of vertical grooves 478 which are laterally offset from the lower ends of the slots 422 formed in the raceway 418. Slidable laterally in a guideway formed by the front wall 476, the block 470 and the forward end of the raceway 418 is a separator plate 480 provided with slots 482 which are normally in register with the slots 422 of the raceway 418. Formed in the block 470 are a plurality of funnel-shaped openings 484 which are arranged respectively below the grooves 478 in the front wall 476 and secured in lower tapered ends of the openings are the upper ends of the plastic nail tubes 197 the lower ends of which fit in the bores 195 in the nail tubes 56, 56a as above explained.

The block 470 has mounted in it a bearing collar 486 and vertically slideable in said collar and resting on the thrust arm 472 is a rod 488 having formed in it a bore adapted to receive a pin 490 which is constantly urged to a raised position in said bore by a spring 492 interposed between the heads of the rod and the pin.

Journalized upon a pin 494 mounted in a bracket 496 secured by screws to the block 470 is an L-shaped lever 498 which is constantly urged counterclockwise as viewed in FIG. 14 by a spring 500 and which is engaged by the upper end of the pin 490. The vertical arm of the L-shaped lever 498 is pivotally connected by a shoulder screw 502, which has a forward extension and has a nut threaded onto it, to the right end (FIGS. 14 and 15) of the separator plate 480.

When the machine is in its rest position the hopper 430 is in its full-line position shown in FIG. 12 and the separator plate 480 is in its position shown in FIGS. 14 and 15 with nails resting in the slots 482 of said plate. As the carrier unit 54 moves to its heel attaching position below the nailing die 44 the piston rod 442 is operated by fluid pressure means hereinafter described to raise the hopper 430 to its dash-line position and to move the thrust arm 472 counterclockwise (FIG. 12) thus allowing the L-shaped arm 498 to be swung counterclockwise (FIG. 14) by the spring 500 until the L-shaped arm engages a stop screw 504 secured to the bracket 496. When this occurs the nails 49 in the slots 482 of the separator plate 480 are transferred to the grooves 478 formed in the front wall 476 and then drop through the funnel-shaped openings 484 into the plastic tubes 197 for delivery to the bores 195 in the nail tubes 56, 56a as above explained.

195 in the nail tubes 56, 56a and into the lower passages 148, 148a of said tubes to positions in which the pointed ends of the nails enter the recesses 58 formed in the heel lift 32 which at this time is in a waiting position beneath the nail tubes. As the vertical arm of the L-shaped lever 498 engages the stop screw 504, the forward extension of the shoulder screw 502 engages a screw 506 secured to an arm 508 which opens a chamber 510 (FIG. 16) of a differential pilot valve 512 to exhaust and thus effects the operation of a plunger 514 of this valve, as will be hereinafter described, whereby to cause the face 456 of the piston 452 to be connected to exhaust. When this occurs the piston rod 442 returns to its lowered starting position under the action of the spring 460 causing the hopper 430 to be moved back to its full-line position and causing the L-shaped lever 498 to be swung clockwise to its position shown in FIG. 14 against the action of the spring 500 and the separator plate to be moved back to its normal position in which its slots 482 register with the slots 422 in the raceway 418. As the abutment 506 is released by the forward extension of the shoulder screw 502 secured to the separator plate 480 the plunger 514 of the differential pilot valve 512 assumes its rest position shown in FIG. 16.

High pressure air used in the operation of the machine is available for a primary supply line 516 which is connected through a ball check to a secondary supply line 518, from a compressor line 520 connected through a pressure regulator 522 to the primary supply line.

After the last 42 carrying the shoe 38 has been positioned on the post 96 of the jack 40, a heel at this time resting on the table 52, the operator simultaneously depresses a pair of spools 524 of manually operated valves 526 against the action of springs 528 causing air in the line 518 to be available for a face 530 of a spool 534 of a main pilot valve 532 thus causing said spool 534 to move to its dash-line position (FIG. 16), an exhaust line 536 at this time being cut off from the line 518 by the spools 524 of the valves 526. As soon as the spool 534 of the pilot valve 532 has been shifted to its dash-line position to start the machine the operator releases the spools 524 of the manually operated valves 526 with the result that these spools move to their idle positions under the action of the springs 528, the spool 534 remaining in its dash-line position. High pressure air in the secondary supply line 518 is now available through line 538, a pressure regulator 540 and a line 542 for a chamber 544 formed by the cylinder 316 and the face 378 of the piston 320 which is operatively connected to the lever 324 of the heel carrier unit 54. The lines 542 and 538 are also connected for one-way flow in an opposite direction through a ball check. When the spool 534 of the main pilot valve 532 is in its dash-line position a line 546, which is open to a chamber 548 formed by the cylinder 316 and the face 380 of the piston 320, is also open to an exhaust port 550 of the main pilot valve. Accordingly, the heel and base lifts 32, 34 supported by the table 52 will be positioned and clamped by the carrier unit 54 with the vertical median plane 386 of said lift arranged in the vertical median plane 375 of the carrier unit and the axis of symmetry of said heel lift coincident with a vertical reference line 384 fixed with relation to said unit.

At this time high pressure air in the line 538 is also available for a sequence valve 552 and when air in this line has built up to a predetermined pressure after the heel and base lifts have been clamped in the carrier unit 54, this sequence valve operates and high pressure air is available for a line 554 open to a chamber 556 of a cut off valve 558 which comprises a spool 560 normally held by a spring 562 in its position shown in FIG. 16 to allow air to flow freely through the chamber 556 to a line 564 having ball and restrictor checks.

The cut off valve 558 serves as a safety to insure against the machine operating through a cycle when there is no work, which may be a heel lift 32 and a base lift 34 or just a heel lift then referred to as a heel, in the carrier

unit 54 of the machine. The spool 560 of the cut off valve 558 has a face 566 open to a line 568 having connected to it a cut off pilot valve 570 which is also connected to the line 542 and is secured, as shown in FIG. 10, to the cylinder 316 pivotally connected to the base plate 300 of the carrier unit 54. The cut off pilot valve 570 has a spool 572 which is normally maintained by a spring 574 in its position shown in FIG. 16 to open the line 568 and accordingly the face 566 of the spool 560 of the cut off valve 558 to an exhaust port 576 of the valve 570.

The spool 572 of the cut off pilot valve 570 is actuated by a striker screw 578 (FIG. 10), which is secured to the lever 324, when said lever is moved counterclockwise (FIG. 10) a distance greater than that required to clamp the smallest heel lift 32 or heel in the carrier unit 54. The spool 572 normally closes off the line 568, which is normally open to the exhaust port 576, from the line 542 but when this spool has been actuated against the action of the spring 574 by the striker screw 578, high pressure air in the line 542 is available for the line 568, which at this time is cut off from the exhaust port 576, with the result that the cut off valve 558 is closed against the action of the spring 562 and high pressure air from the line 554 is no longer available for the line 564 and, as will appear later, operation of the machine ceases. The piston 320 may be restored to its starting position to open up the various clamps of the carrier unit 54 in response to the manually moving of the spool 534 from its dash-line position to its full-line position by the use of a rod 534a which is secured to the spool and slidably fits in a bore of the casing of the main pilot valve.

The line 564 is open to the chamber 409 formed by the cylinder 392 and the face 404 of the piston 396 and when high pressure air is available for this line the arm 302 of the carrier unit 54 is moved from its position shown in FIG. 3 to the heel attaching or waiting position in which the heel 30 in said unit is arranged just below the nailing die 44 as above explained, the chamber 402 formed by the cylinder 392 and the face 406 of the piston 396 being open to the exhaust port 550 of the main pilot valve 532 through a line 530, a sequence valve 532 and the line 546. Movement of the transfer arm 362 to the position in which the carrier unit 54 is in its heel attaching position or at a heel attaching station below the nailing die 44 causes the plunger 414 of the pilot valve 412, by reason of its engagement with the screw 416, to move to its dash-line position shown in FIG. 16 against the action of a spring 584, thus allowing high pressure air in the line 538 at this time open through a piloted valve 586, a line 590, and the then open pilot valve 412 to be available for a line 592 which has ball and restrictor checks and is open to the face 456 of the piston 452 which is slideable in the cylinder 454.

Upward movement of the piston 452 in the cylinder 454 against the action of the spring 469 causes said hopper 430 to be raised to its dash-line position (FIG. 12), the separator plate 430 to slide to the right (FIGS. 14 and 15) and the arm 508 of the differential pilot valve 512 to be swung clockwise (FIG. 16).

As the arm 508 of the differential pilot valve 512 is moved clockwise (FIG. 16) air is bled from the chamber 510 of this valve thus causing the spool 514 of this valve to move to its dash-line position shown in FIG. 16. Movement of the spool 514 of the differential pilot valve 512 to its dash-line position allows high pressure air in the line 538 to flow through this valve and into a line 604 causing it to operate against a face 606 of a spool 608 of a pilot valve 610 to allow high pressure air in the line 564 to be available for a line 612 and to operate against a face 614 of a spool 616 to a piloted valve 618 whereby to move this spool against the action of a spring 620 to its dash-line position. At this time a face 622 of the spool 608 of the pilot valve 610 is open through a line 624 and the line 546 to the exhaust port 550 of the main pilot valve 532.

The piloted valve 586 comprises a spool 594 which is

reciprocable in a bore of a cylinder 596 and has a face 598 against which pressure may be applied to move against the action of a spring 599 the spool in said bore between its full-line position shown in FIG. 16 and a position in which it closes the line 538 off from the line 590. The piloted valve 586 also has an exhaust port 600 which is open to the line 590 when this valve is closed as will appear later.

High pressure air in the line 612 which has ball and restrictor checks now operates against the face 598 of the spool 594 of the piloted valve 586 to move this spool to its dash-line position shown in FIG. 16 and to close off the line 590 from the pressure line 538 and to open it to exhaust port 600 thus allowing the piston 452 to be returned to its lowered starting position under the action of the spring 460 whereby to return the separator plate 430 to its starting position, to move the hopper 430 from its raised dash-line position to its lowered full-line position and to allow the lever 508 of the differential pilot valve 512 to be spring actuated to seal the chamber 510. Pressure is now built up in the chamber 510 of the differential pilot valve 512 and the spool 514 of this valve moves from its dash-line position to its full-line position (FIG. 16).

When the spool 616 of the piloted valve 618 has been moved to its dash-line position, high pressure air in the secondary supply line 518 is available for a line 626 connected by a pressure regulator 628 and a sequence valve 630 to a line 632 open to a face 634 of the piston 136 which is slideable in the cylinder 134 and supports the jack post 36. At this time a face 636 of the piston 136 is open to a line 638 which is open to the exhaust port 550 of the main pilot valve 532. The lines 632 and 626 are connected directly through a ball check 640 to permit exhaust of air from below the piston at the proper time in the sequence of operations. When high pressure air and air open to exhaust is available for the faces 634, 636 respectively of the piston 136 the jack post 96 is raised to force the heel seat 36 of the shoe 38 against the heel 30 held in its waiting position in the carrier unit 54 and then to force the heel against the bottoms of the nail tubes 56, 56a with substantial upward pressure.

When the work is clamped in the machine air pressure in the line 626 builds up and operates a sequence valve 642 causing high pressure air to be available for a line 644 which includes ball and restrictor checks and is open to the chamber 270 formed by the fixed cylinder 216 and a face 274 of the piston 212 movable in said cylinder. Air under pressure in the line 644 is also available for a face 646 of a spool 648 of a pilot valve 650 causing said spool to be moved to its dash-line position (FIG. 17) against the action of a spring 652 whereby to open a line 654 to an exhaust port 656 of this pilot valve to the chamber 272 which is formed by the fixed cylinder 216 and the face 276 of the piston 212. As above explained, the piston 212 is secured to the upper end of the connecting rod 210 which has the barrel 226 of the gun 46 secured to it. Accordingly, when air under high and exhaust pressures is available for the chambers 270, 272 respectively the barrel 226 of the gun 44 is lowered freely until such time as the hammer 234 of the gun has forced the drivers 150 against the upper ends of the nails 49 the lower pointed ends of which are in the recesses 58 of the heel 30 and the upper ends of which are in the bores 148a of the nail tubes 56, 56a. As this occurs, the rear face of the carrier block 238 which is secured to the barrel 226 of the gun 46 moves the spool 278 of the pilot valve 280 against the action of a spring 658 to its dash-line position. The line 644 is now open through a sequence valve 660, a line 662, the differential pilot valve 286, a line 664, the pilot valve 280 and a line 666 to a face 668 of a spool 670 of a pilot valve 672 with the result that the spool moves to its dash-line position against the action of a spring 674 thus opening the primary supply line 516 to a line 676 connecting the pilot valve 672 to the chamber 204 of the gun 46. When air builds up in the chamber 204 of the gun 46, the inertia block 232 of the

gun is reciprocated at a high speed in the upper bore 228 of the gun causing the hammer 234 to operate with impact action against the drivers 150 to drive the nails 49 into the heel 30 and the heel seat 36 of the shoe 38, the nails being clinched against the heel plate 69 of the last 42 as shown in FIG. 7 and the gun following the hammer downward as the nails are driven into the work. It will be apparent that since the jack post 40 is urged upward by air pressure there will be some compression of air beneath the piston 136 and accordingly a very slight downward yield of said piston as the result of the successive downward heavy impacts of the drivers 150 against the nails being driven into the work.

When the nails have been completely driven into the work the cam plate 282 initially secured to the carrier block 238 of the gun 46 engages the lever 283 which is operatively connected to the spring-pressed plunger 284 of the differential pilot valve 286 causing air to be bled from the chamber 290 of this valve with the result that the spool 288 of the valve moves to its dash-line position cutting off the supply of high pressure air from the face 668 of the spool 670 whereupon this spool returns under the action of the spring 674 to its idle full-line position and cuts off the supply of high pressure air for the chamber 204 of the gun and opens this chamber to an exhaust port 682 of the pilot valve. When the spool 288 of the differential pilot valve 286 has moved to its dash-line position high pressure air in the line 662 is open, through the differential pilot valve and a line 687, to a face 638 of the main pilot valve 532 with the result that the spool 534 of this valve is moved to its full-line starting position shown in FIG. 16. If desirable a sequence valve (not shown) may be inserted in the line 687 to delay momentarily the reversal of the spool 534.

The working portion of the machine cycle having been completed high pressure air is now available through the line 546 for the face 380 of the piston 320 while the face 378 of this piston is open to an exhaust port 690 of the main pilot valve 532 causing the piston to move the various clamps of the carrier unit 54 away from the heel and base lifts 32, 34 which have been attached to the shoe 38. It will be noted that at this time the exhaust port 690 of the main pilot valve 532 is open through lines 538, 554, the cut off pilot valve 558, the line 564, the pilot valve 610, and the line 612 for the face 614 of the spool 616 of the piloted valve 618 with the result that the line 626 is cut off from the secondary supply line 518 and is open to an exhaust port 692 of the piloted valve 618. When the face 598 of the piloted valve 586 is open to exhaust the spool 594 of the piloted valve 586 is reset to the position shown in FIG. 16 by the spring 599.

High pressure air from the line 546 is also available at this time through the line 638, which has a restrictor check, for the face 636 of the piston 136 while the face 634 of this piston is open to the exhaust port 692 of the valve 618 and accordingly, the jack post 96 is moved to its lowered position preparatory to removing from said post the shoe to which the heel has been attached. The opening of the line 626 and accordingly the face 646 of the pilot valve 650 to exhaust causes the spool 648 of this valve to return to its full-line position shown in FIG. 17 under the action of the spring 652 with the result that the chamber 272 of the cylinder 216 is open to high pressure air from the secondary supply line 518, the chamber 270 of this cylinder at this time being open to the exhaust port 692. Accordingly, the gun 46 which is secured to the piston rod 210 of the piston 212 reciprocable in the cylinder is moved to its raised starting position. The differential pilot valve 286 is reset by residual pressure in the line 662 after the cam plate 282 has moved away from the plunger 284 of the differential pilot valve 286. If desirable the plunger 288 of the pilot valve 286 may be biased to its idle position by a light spring for example or by other resetting means common to commercial valves of this type.

High pressure air in the line 546 is also available through the sequence valve 582 and the line 580 for the face 406 of the piston 396 and the face 404 of this piston is open to the exhaust port 690 of the valve 532 causing, after the jack post 96 has been lowered and the gun has been raised, the carrier unit 54 to be returned to its loading position above the table 52. High pressure air in the line 580 also serves to reset the spool 608 of the pilot valve 610 by reason of its acting against the face 622 of this valve the face 606 of the spool at this time being open to the exhaust.

Should the machine be stopped as above described by the operation of the cut-off valve 558 when there is no work in the heel carrier unit 54, the various clamps of this unit may be operated to their starting positions by manually moving the plunger 534 of the main pilot valve 532 from its dash-line to its full-line position. After opening up the various work clamps of the heel carrier unit 54 and placing a heel and base lift on the table 52 the machine may be started through its cycle by depressing the plungers 524 as above described. It will be appreciated that the showing in FIGS. 16 and 17 of the drawings is merely schematic for the purpose of correlating the operation of the various instrumentalities of the machine and that the different types of valves, pressure regulators, and checks may be obtained commercially to produce the desired result.

The magazine 50 comprises an upstanding sheet metal casing 700 (FIGS. 18 and 19) which, for the most part, is generally U-shaped in horizontal cross section and is of suitable size and shape to house in stacked relation the heel and base lifts 32, 34 which are alternately arranged heightwise in the casing as shown in FIG. 19. The lower end of the casing has welded to it a bottom flange 702, which has at its forward end an upstanding margin, and the upper end of the casing has welded to it a cover 704. Movable in a slot 705 formed in the upstanding margin of the bottom flange 702 of the casing 700 is a lift retaining member 706 which when slid to a rearward lift retaining position shown in dash lines extends through an opening 707 at the rear of the casing and rests on said bottom flange, said member serving to insure against the alternate heel and base lifts 32, 34 falling out of the casing between the time that it is loaded and the time that it is secured in an operating position above the carrier unit 54 of the machine.

The cover 704 of the casing 700 has secured to it a handle 708 and also a hook 710 which is constructed and arranged to fit on a pin 712 secured to the upstanding forward end of a bracket 714 fixed to the vertical column 64. Secured by screws 716 to the cover 146 of the multipart nailing die 44 is a holder 718 having a U-shaped opening 719 which is spaced from and overlies the U-shaped opening 312 of the cover 308 of the carrier unit 54 when said unit is in its rest position shown in FIG. 19. The holder 718 comprises side plates 718a which are flared at their forward ends, and a back plate 718b.

Secured to the left side plate 718a of the holder 718 (as viewed from the front of the machine) is a cylinder 720 (FIGS. 16, 18 and 19) having slidable in a bore thereof a piston 722 carrying a presser rod 724 which normally extends through alined recesses in the casing 700 and in the left side plate 718a of the holder 718 and presses against a heel lift 32 in the casing.

To fill the empty casing 700 of the magazine 50 it is customary, after causing the pressure rod 724 to be withdrawn to a position outside of the casing, to lift the magazine by the use of the handle 708 off the pin 712 and to remove the casing from the holder 718. After filling the casing 700 of the magazine 50, while it is upside down, with alternating heel lifts 32 and base lifts 34 (the last lift placed in the casing being a base lift) the retaining member 706 is slid to a dash-line position shown in FIG. 18 to confine the heel and base lifts in the casing 700 as it is being mounted in its operating position in

the machine, the casing being replaced in its operating position with its hook 710 on the pin 712 and its bottom flange 702 arranged adjacent to the cover 308 of the carrier unit 54 and resting against the side and rear plates 718a and 718b of the casing.

When the casing 700 of the magazine 50 has been installed on the carrier unit 54 of the machine, the retaining member 706 is pulled forward to its full-line position shown in FIG. 18 allowing a base lift 34 and a heel lift 32 to drop through the U-shaped opening 312 of the cover 308 and to be supported by the table 52 between the various clamps of the carrier unit 54.

Preparatory to removing the casing 700 of the magazine 50 from the machine for the purpose of refilling it, the presser rod 724 is moved to an inactive or retracted dash-line position (FIG. 18) to the left of the casing 700 by mechanism which will now be described. The arm 302 (FIG. 3) of the carrier unit 54 has secured to it a pilot valve 728 (FIGS. 3 and 16) comprising a cylinder 730 having a bore in which a spool 732 is slidable, the spool normally being retained in its full-line or rest position shown in FIG. 18 by a spring 734. Air from the secondary supply line 518 is normally available through a passage 735 formed in the spool 732 and a line 737 (FIGS. 3, 16 and 18) for a chamber 736 formed by the cylinder 720 and a face 738 of the piston, a chamber 740 formed by the cylinder and a face 742 of the piston 722 being open through a line 743 to an exhaust port 744 (FIG. 16) of the pilot valve 728.

When the carrier unit 54 is swung about the bearing pin 304 to a position in which the heel and base lifts 32, 34 in this unit are arranged in their heel attaching positions below the nailing die 44 ready to be attached to the shoe, the spool 732 of the pilot valve 728 has engaged an abutment screw 746 (FIG. 3) attached to the column 64 with the result that the spool of this valve moves to its dash-line position (FIG. 16), air under high and exhaust pressures at this time being available for the chambers 740, 736 respectively of the cylinder 720 and accordingly the presser rod 724 is moved to its dash-line position shown in FIG. 16 out of the casing 700 of the magazine 50. When this occurs the lowermost heel and base lifts 32, 34 in the casing 700 of the magazine drop down onto the top of the carrier unit cover 308 which at this time has been swung into a position beneath said casing.

As the carrier unit 54 swings away from its heel attaching position beneath the nailing die 44 near the end of the cycle of the machine, the pilot valve 728 is moved away from the stop screw 746 and accordingly, the spool 732 is returned by the spring 734 to its full-line position (FIG. 16) and accordingly, air under high and exhaust pressures is available for the chambers 736, 740 respectively in the cylinder 720 causing the pressure rod 724 to move against the side of the second heel lift 32 from the bottom of the stack of heel and base lifts which at this time are in the casing 700. When the U-shaped opening 312 of the cover plate 308 of the carrier unit 54 is in its loading position below the casing 700 of the magazine 50 the lowermost base lift 34 and the heel lift 32 above it drop onto the table 52, the second base lift in the stack of lifts being free and resting just above the cover 308 of the carrier unit. The presser rod 724 during this time exerts pressure against the then lowermost heel lift 32 in the casing 700 to prevent the weight of the stack of heel and base lifts from resting on the cover plate 308 of the carrier unit 54. When the carrier unit 54 approaches its heel attaching position beneath the nailing die 44, the presser rod 724 is again retracted as above described thus allowing the first heel lift 32 and the second base lift 34 in the magazine to drop into the lower end of the casing 700 below the path of movement of the presser rod.

It will be apparent that the presser rod 724 has to be withdrawn from the casing 700 of the magazine 50 before said casing can be removed from the machine for the pur-

pose of refilling. When it is desired to operate the presser rod 724 for this purpose the operator may manually slide the spool 732 of the valve 728 to the right (FIG. 3) against the action of the spring 734 thus causing the presser rod to be moved to its retracted dash-line position out of the magazine casing 700. After removing the casing 700 from its fixed position above the carrier unit 54 the operator releases the spool 732 and after again loading the magazine the presser rod 724 is again temporarily retracted by pressing against the spool 732 to enable the operator to insert the magazine in its active position in the machine. The spool 732 is then released causing the presser rod 724 to be moved to its active position against the side of the second heel lift 32 from the bottom of the casing 700 of the magazine 50. The retaining member 706 is then drawn forward to its full-line position shown in FIG. 18 with the result that the lowermost base lift 34 with the lowermost heel lift 32 on top of it drops between the clamps of the carrier unit 54 ready to be positioned and clamped to said unit during the next cycling of the machine.

If desirable the spool 732 of the pilot valve 728 may be manually actuated while the carrier unit 54 is in its rest position shown in FIG. 3 by a solenoid (not shown) operated by a switch (not shown) located at a convenient position on the machine.

When the cut-off valve 558 has been closed to stop the normal cycle of the machine, instead of restoring the clamps of the heel gage to their rest positions by resetting the spool 534 of the main pilot valve 532, as above described, said clamps may be restored to their idle positions by the use of a manually operated valve 539 which is interposed in the lines 538 and 546. When the machine is stopped by the closing of the cut-off valve 558 the operator moves a spool 539a of the valve to a dash-line position whereby to cause the various clamping members of the heel gage to open, and after inserting a heel in the gage moves the spool back to its full-line position to start the machine through its cycle.

Having thus described our invention, what we claim as new and desire to secure by Letters Patent of the United States:

1. In a machine for operating upon shoes, a support, a nailing die, means for effecting relative movement between the support and the die to force two parts of a shoe together, means cooperating with the nailing die to drive a plurality of nails simultaneously by successive impact action into said shoe parts to secure said shoe parts to each other, and means for allowing the support to move slightly away from the nailing die in response to the driving of nails into the work by said second-named means.

2. In a heel attaching machine, a support, a nailing die having passages, means for effecting relative movement between the support and the nailing die to force together a heel and a heel seat of a shoe, a gun which is movable toward and away from the nailing die, a plurality of drivers movable between retracted and projected positions in the passages of said die, means for moving the drivers to and holding them in their retracted positions in the passages of the die, a hammer which is movable in the gun and engages the drivers, said drivers being moved into engagement with nails resting in the passages of the nailing die in response to movement of the gun toward said die, and means operative in response to further movement of the gun toward the die for causing the hammer operating through the drivers to drive said nails with successive impact action into the heel and the heel seat of the shoe whereby to attach the heel to the shoe.

3. In a heel attaching machine, a support, a nailing die, means for effecting relative movement between the support and the nailing die to force together a heel and a heel seat of a shoe, means cooperating with the nailing die to drive a plurality of nails simultaneously by suc-

cessive impact action into the heel and the heel seat of the shoe to attach the heel to the shoe, and resilient means which is adapted to allow said support to move slightly away from the nailing die in response to the driving of nails into the heel and the heel seat of the shoe by said second-named means and is adapted to cause said support to move slightly toward the nailing die intermittently with the driving of said nails.

4. In a heel attaching machine, a jack for receiving a shoe, a nailing die having passages, means for positioning a heel relatively to the jack and the die, mechanism for causing the jack to move yieldingly toward the nailing die to force that heel seat of the shoe against the heel and to force the heel against the nailing die, drivers movable in the passages of the nailing die, means for delivering nails to the passages of said die, and means for applying a plurality of impacts to the drivers to cause them to drive said nails into the heel seat of the shoe and into the heel whereby to attach the heel to the shoe, said mechanism being adapted to allow the jack to move away from the nailing die under the impact action of the drivers.

5. In a heel attaching machine, a jack for receiving a shoe, a nailing die having passages, means for positioning a heel relatively to the jack and the die, mechanism for moving the jack toward the nailing die to cause the heel and the heel seat of the shoe to be clamped together and the heel to be forced against the nailing die, a plurality of drivers movable between retracted and projected positions in the passages of the nailing die, means for delivering nails to the passages of said die, means for moving the drivers to their retracted positions preparatory to delivering nails to said passages, a gun comprising an impact member and a hammer which is in engagement with the drivers, means for moving the gun toward and away from the nailing die, and means responsive to movement of the gun toward the nailing die for causing said member to apply a plurality of impacts to the hammer and through said hammer to each of the drivers to drive nails in the passages of the die into the heel and the heel seat of the shoe whereby to attach the heel to the shoe.

6. In a heel attaching machine, a support, a nailing die having passages, means for delivering nails to said passages, drivers movable in said passages, means for moving the support with relation to the nailing die to force a heel seat portion of a shoe against the heel and the heel against the nailing die, means for imparting a plurality of successive blows to the drivers to cause them to drive nails intermittently into the heel and the heel seat of the shoe whereby to attach the heel to the shoe, and resilient means for causing the support to yield in response to pressure of the work against it as the nails are being driven into said work.

7. In a heel attaching machine, a jack having interlocking means adapted to cooperate with interlocking means on a last carrying a shoe to position the last and accordingly the shoe in a predetermined fixed relation on the jack, said jack being movable in a rectilinear path extending heightwise of the shoe and being constrained against movement lengthwise and widthwise of the shoe, and means comprising a plurality of movable members adapted to position and to clamp a heel and to move it to a position in which its margin is in register lengthwise of said path with but is located a predetermined distance outside of the feather line of the shoe positioned on the jack.

8. In a heel attaching machine having a shoe supporting jack and heel attaching means relatively movable heightwise of a shoe on said jack to attach the heel to the shoe, said jack having means including a spindle for engaging a thimble hole in the heel end of a last upon which the shoe is mounted for locating the heel seat face of each shoe with its curved edge in a predetermined relation to said spindle, a carrier unit, means for automatically deliver-

ing heels to said unit, means for automatically positioning and clamping a heel in said unit, and means responsive to clamping of the heel in said unit for moving the heel to a predetermined position adjacent to the heel attaching means with the edge face of the heel in a predetermined relation to the curved edge of the heel seat of the shoe.

9. In a heel attaching machine having last and shoe supporting means and heel attaching means relatively movable only heightwise of a shoe on said supporting means to attach a heel to a shoe, said supporting means having means which includes a pin fixedly fastened to said supporting means and adapted to engage the thimble in the heel end of each last for locating the shoe with the curved edge of its heel seat face symmetrical with the axis of said last pin and with the vertical median plane of its heel seat face lying in a fixed reference plane of the machine, and means for presenting a heel in position to be attached to a shoe on said support, said heel presenting means having gages movable to position heels of different sizes each with its vertical median plane lying in the fixed reference plane of the machine and with its axis of symmetry arranged in a fixed predetermined relation to the axis of said last pin and lying in said reference plane whereby to enable the heel and the heel seat of the shoe to be pressed together in the proper relation as the result of the relative movement between the jack and the heel attaching means preparatory to the attachment of the heel to the shoe.

10. In a heel attaching machine, a carrier unit movable between a heel loading position and a heel attaching position, means for supporting a heel, an abutment adapted to engage the breast of the heel, members adapted to engage the rear lateral margins of said heel, and means for moving said abutment on the one hand and said members on the other hand at proportional rates to move the heel, irrespective of its size, to a clamped position in which a vertical median plane of the heel lies in a fixed vertical median plane of the carrier unit and in which the axis of symmetry of the heel is arranged in a fixed axis of said carrier unit.

11. A heel clamp comprising an abutment adapted to engage the breast of a heel, members adapted to engage the rear lateral margins of said heel, and means for moving said abutment on the one hand and said members on the other hand at predetermined proportional rates to move the heel, irrespective of its size, to a clamped position in which its vertical median plane coincides with a fixed reference plane of the clamp and its axis of symmetry is arranged in a fixed axis of said clamp.

12. In a heel attaching machine, a nailing die, a jack having one or more elements arranged in fixed positions and adapted to receive interlockingly one or more elements of any one of a run of lasts of different sizes to locate the heel seat of a shoe mounted on said last, means for moving the jack only in a rectilinear path, means for automatically positioning a heel, which has an outline substantially similar to but larger than the feather line of the heel seat of the shoe, adjacent to said nailing die with its lateral and rear margins in register lengthwise of said path with but located a predetermined distance outside of the feather line of the heel seat of said one shoe, and means for moving the jack lengthwise of said path to force the heel seat of the shoe against the heel and the heel against the nailing die.

13. In a machine for use in the attachment of heels to shoes, a table for supporting a heel, a carrier unit, means for positioning and clamping in the carrier unit any one of a plurality of heels which are supported by the table with their vertical median planes respectively arranged in a fixed reference plane of the carrier unit and with their axes of symmetry respectively arranged in a fixed axis of said unit, a jack having a spindle adapted to receive the thimbles of lasts which carry shoes and the rear ends of the heel seats of which are graduated different distances

from the axes of the thimbles of the lasts in accordance with the sizes of the shoes, means for orienting the lasts about the axis of the spindle of the jack to move the vertical median planes of the heel seats of the lasts into coincidence with a fixed reference plane of the machine, means for moving the carrier unit into a position in which the vertical median plane of the heel clamped in said unit is arranged in said reference plane of the machine and in which the axis of symmetry of the heel is arranged parallel to and spaced a predetermined fixed distance from the axis of the spindle irrespective of the size of the heel, and means for effecting rectilinear movement of the jack lengthwise of the axis of the spindle to force together the heel and the heel seat of the shoe preparatory to attaching the heel to the shoe.

14. In a heel attaching machine, a support for a heel lift and a base lift, a gage for positioning the heel lift and the base lift with relation to the support, said gage comprising a breast clamp and a pair of side clamps opposed ends of which carry abutment members adapted to yield under pressure, means for positively moving at one rate the breast clamp against the breast faces of the heel and base lifts causing these faces to be alined and for simultaneously moving at another rate the side clamps toward each other against the rear lateral sides of the heel lift causing them to cooperate with the breast clamp in positioning the heel lift, irrespective of its size, with its vertical median plane arranged in a fixed reference plane of the gage and with its axis of symmetry coincident with a fixed reference axis of the gage, said abutment members mounted on the side clamps being adapted, as they are moved toward each other with said side clamps, to bear against the rear portions of the sides of the base lift to hold it clamped against the breast clamp with its side and rear margins projecting beyond the side and rear margins of the heel lift.

15. In a heel attaching machine, a carrier unit movable between a heel loading position and a heel attaching position, means for supporting a heel, an abutment adapted to engage the breast of the heel, members adapted to engage the rear lateral margins of the heel, means for moving, when the carrier unit is in its loading position, said abutment on the one hand and said members on the other hand at proportional rates to move on said first-named means the heel, irrespective of its size, to a clamped position in which a vertical median plane of the heel lies in a fixed vertical median plane of the carrier unit and in which the axis of symmetry of the heel is arranged in a fixed axis of the carrier unit, and fluid pressure means operated in timed relation with the last-named means for moving the carrier unit to its heel attaching position.

16. In a heel attaching machine, a table for supporting a heel, a carrier unit having a median reference plane and clamps which are movable toward and away from each other at predetermined rates in a plane arranged generally at right angles to said reference plane, means for moving said clamps toward each other to position any one of a run of heels with its vertical median plane arranged in said reference plane of the carrier unit and with its axis of symmetry arranged in a fixed axis of the unit which axis is arranged in said fixed reference plane and is disposed generally at right angles to the plane of movement of the clamps, a jack having a spindle adapted to receive the thimbles of lasts which carry shoes and the rear ends of which are spaced graduated distances from the axes of the thimbles of the lasts in accordance with the sizes of the shoes, means for orienting the lasts and accordingly the shoes on them about the axis of the spindle of the jack to move the vertical median planes of the heel seats of the lasts into coincidence with a fixed reference plane of the machine, means for moving the carrier unit into a position in which the vertical median plane of the heel clamped in the unit is arranged in said reference plane of the machine and in which the axis of symmetry of the heel is arranged parallel to and spaced a

fixed predetermined distance from the axis of the spindle, irrespective of the size of the heel, and means for effecting rectilinear movement of the jack lengthwise of the axis of the spindle to force the heel and the heel seat of the shoe together preparatory to the attachment of the heel to the shoe.

17. In a heel attaching machine, a table for supporting a heel lift and its associated base lift, a carrier unit movable between a loading position and a heel attaching position, said carrier unit comprising a breast clamp and side clamps, means for moving said breast and side clamps inwardly in a general plane at predetermined ratios causing the breasts of the heel and base lifts to be forced with gripping pressures in alined relation against the breast clamp with the heel lift, irrespective of its size, arranged with its vertical median plane arranged in a fixed median reference plane of the carrier unit and its axis of symmetry arranged in said median reference plane and disposed at right angles to the general plane of movement of the clamps, a jack having a spindle adapted to receive the thimbles of lasts which carry shoes and the rear ends of the heel seats of which are graduated different distances from the axis of the thimbles of the lasts in accordance with the sizes of the shoes, means for orienting the lasts about the axis of the spindle of the jack to move the vertical median planes of the heel seats of the lasts into coincidence with a fixed reference plane of the machine, means for moving the carrier unit into a position in which the vertical median plane of the heel clamped in said unit is arranged in said reference plane of the machine and in which the axis of symmetry of the heel is arranged parallel to and spaced a predetermined fixed distance from the axis of the spindle irrespective of the size of the heel, and means for effecting rectilinear movement of the jack lengthwise of the axis of the spindle to force together the heel and the heel seat of the shoe preparatory to attaching the heel to the shoe.

18. In a heel attaching machine, a support for a heel, a gage for positioning and clamping said heel, said gage comprising a breast clamp, a back clamp and front and rear pairs of side clamps, and means for yieldingly moving at different speeds against the rear face and forward portions of the side faces of the heel the back clamp on the one hand and the front pair of side clamps on the other hand to locate the heel approximately in a desired position on the support and for then moving at a predetermined ratio the breast clamp and the rear pair of side clamps against the breast of the heel on the one hand and the rear side portions of the heel on the other hand positively to move a vertical median plane of the heel, irrespective of its size, into coincidence with a fixed reference plane of the gage and for moving an axis of symmetry of the heel into coincidence with a fixed gage reference axis which lies in said reference plane of the gage and is disposed at right angles to the tread face of the heel.

19. In a heel attaching machine, a nailing die arranged at a heel attaching station, a carrier unit comprising clamps, means for operating said clamps when the carrier unit is at a loading station to position the heel in and secure it to the unit, means for moving the carrier unit from said loading station to said heel attaching station whereby to position the heel adjacent to the nailing die, a jack for a shoe, means for moving from a retracted position the jack toward the nailing die to force the heel seat of the shoe against the heel and the heel against the nailing die, means cooperating with the nailing die to drive nails into the heel and the heel seat of the shoe to attach the heel to the shoe, and means for moving the clamp away from the heel which has been attached to the shoe preparatory to moving the jack back to its retracted position.

20. In a heel attaching machine, a nailing die comprising a fixed casing, nail tubes supported in said casing for initial adjustment into different nail design positions,

and means comprising a cam for simultaneously imparting rectilinear movement to some of the nail tubes in said casing and combined rectilinear and swinging movement of the other tubes of said casing.

21. In a heel attaching machine, a nailing die comprising end and side nail tubes arranged about a design axis, holder plates secured respectively to the tubes, a fixed casing having one or more guideways along which the end nail tubes may be moved, guide members carried by the holder plates, said casing having fixed guide slots in which the guide members are movable for restraining said guide members in rectilinear paths extending toward and away from the design axis, a cam which is movable into different adjusted positions with relation to the casing and has one or more ways adapted, during movement of the cam, to move the guide members mounted on the holder plates and controlled by the guide slots in the casing toward and away from said design axis, each of the holder plates of the side nail tubes having secured to it a follower which is spaced from its associated guide member, said cam having ways along which said followers respectively engage and which are adapted to cause associated holder plates of the side nail tubes to swing about the guide members as said guide members move along the guide slots in the casing whereby to move the side nail tubes into the desired positions to accommodate different sizes of work.

22. In a heel attaching machine, a nailing die comprising a fixed casing having rectilinear guideways, end nail tubes mounted for rectilinear movement in said guideways, side nail tubes arranged at opposite sides of said end nail tubes, holders secured respectively to said end and side nail tubes, guide rolls mounted on the holders of each of the end nail tubes, a guide roll and a swing roll mounted on each of the holders of the side nail tubes, each swing roll being journaled for rotation about its corresponding guide roll, said casing having converging guide slots which converge toward a central axis of the die and are adapted to receive respectively the guide rolls mounted on the holders, a cam which has ways for receiving respectively the guide rolls and the swing rolls which are mounted on the holders, and means for moving the cam into different adjusted positions to cause the guide rolls to move along the guide slots on the casing whereby to move the tubes toward and away from the central axis of the die and also to cause the swinging rolls to swing about their corresponding guide rolls whereby to move the nail tubes into the desired nail design positions to accommodate different sizes of work.

23. In a heel attaching machine, a nailing die having a plurality of passages, means for delivering nails to said passages, drivers movable in said passages, means for positioning a heel adjacent to the ends of the passages, means for forcing the heel seat of a shoe against the heel and said heel against a portion of the nailing die bordering the ends respectively of said passages, a gun comprising a barrel which has a bore and is movable in a rectilinear path toward and away from the nailing die, an extractor plate which is adapted slidingly to support said drivers and which is mounted for movement with and for yielding movement with relation to said barrel lengthwise of said path, a hammer which is arranged in the bore of the barrel and is movable with and relatively to said barrel lengthwise of said path, a weighted piston which is reciprocable in the barrel and is adapted successively to strike said hammer, power means for moving the barrel toward and away from the nailing die, and power means responsive to movement of the barrel toward the nailing die for effecting reciprocation of the piston in said barrel whereby to cause said piston intermittently to strike the hammer and the hammer to cause the drivers to drive nails into the heel seat of the shoe and the heel to attach the heel to the shoe.

24. In a heel attaching machine, a support for a shoe, a nailing die having passages, means for positioning a heel

relatively to the nailing die, means for effecting relative movement between the support and the nailing die to force together the heel and a heel seat of the shoe, drivers movable in the passages of the nailing die, means for delivering nails to said passages, a gun barrel movable toward and away from the nailing die in a rectilinear path extending lengthwise of the passages of said die, an extractor plate which is yieldingly supported by said barrel and is adapted to assist the passages of the nailing die in guiding said drivers and to permit movement of the drivers lengthwise therein and also to extract said drivers from said passages by engagement with heads of said drivers, power means for moving the gun barrel in opposite directions in said rectilinear path, a hammer reciprocable in said barrel and adapted to be moved lengthwise of said rectilinear path with the barrel, an inertia block adapted to be moved lengthwise of said rectilinear path with the barrel and adapted to be moved in said barrel to impart a series of blows against the hammer and thus cause said hammer successively to impart a series of blows to the drivers as the gun is moved in said path toward the nailing die whereby to drive nails in the passages into the heel and the heel seat of the shoe, means responsive to movement of the barrel toward the nailing die in said path to a predetermined position for rendering said inertia block active to cause the nails to be driven into the heel and the heel seat of the shoe, and means responsive to movement of the barrel toward the nailing die to another predetermined position in said path for rendering said inertia block inactive whereby to stop the driving of the nails and for causing said barrel, together with the inertia block, the hammer and the drivers, to be moved in opposite directions in said rectilinear path.

25. In a heel attaching machine, a jack for a shoe mounted on a last, a nailing die having passages, a carrier unit for positioning a heel, means for moving the jack with relation to the nailing die to force the heel seat of the shoe against the heel and the heel against the nailing die, driving means comprising a gun barrel having bores, an extractor yieldingly supported by the barrel and having slots, drivers which have heads and are slidably mounted in the slots of the extractor and are adapted to be supported by their heads by said extractor, a hammer slidable in one of the bores and adapted to engage the heads of the drivers, an inertia block slidable in the other of said bores and adapted to strike the hammer with successive impact actions, power means for moving the gun barrel toward the nailing die to cause the drivers, the hammer and the impact block to be moved toward the nails in the passages of the nailing die, means responsive to movement of the gun barrel to a predetermined position for effecting vibratory movement of the inertia block in its associated bore in the barrel to cause the hammer successively to strike the drivers with successive impact actions and thus to drive nails into the heel and the heel seat of the shoe, and thus to permit the barrel to be moved by said power means toward the nailing die to an extent controlled by the driving of the nails into the heel and the heel seat of the shoe, and means responsive to movement of the barrel to a predetermined position for rendering the inertia block inactive to cause movement of said block and accordingly movement of the gun barrel toward the nailing die to cease, and thereafter said barrel to move in its rectilinear path away from the nailing die, said extractor serving, as the barrel moves away from the nailing die, to move the drivers along the passages of the nailing die to their starting positions by engagement with the heads of said drivers.

26. In a heel attaching machine, a nailing die having a plurality of passages, means for delivering nails to said passages, drivers movable in said passages, means for positioning a heel adjacent to the ends of said passages of the nailing die, means for forcing a heel seat of a shoe against the heel and said heel against a portion of

the nailing die bordering the ends respectively of said passages, a barrel which has a bore and is movable in a rectilinear path toward and away from the nailing die, an extractor plate which is adapted slidably to support said drivers and which is mounted for movement with and for yielding movement with relation to said barrel lengthwise of said path, a hammer which is movable with and relative to the barrel in said bore lengthwise of said path, a weighted piston which is movable in the barrel toward and away from said hammer and is adapted to impart successive rapid blows to said hammer, power means for moving the barrel toward and away from the nailing die, means responsive to movement of the barrel to a predetermined position toward the nailing die for effecting reciprocation of the piston in said barrel thereby causing said piston intermittently to strike the hammer and the hammer intermittently to strike the drivers causing the nails to be driven into the heel seat of the shoe and the heel whereby to attach the heel to the shoe, and means for rendering said power means inactive when the barrel has moved to a predetermined position whereby to stop movement of said weighted piston and said impacts which are imparted to the hammer and through the hammer to the driver and for thereafter reversing movement of the barrel in said rectilinear path.

27. A heel attaching machine comprising a carrier unit which is movable between a heel loading position and a heel attaching position and which includes mechanism for positioning and clamping a heel in said unit, and means responsive to the operation of said mechanism for insuring against movement of the carrier unit from its loading to its heel attaching position when there is no heel in the carrier unit at its loading position.

28. In a heel attaching machine, a support for a shoe, a nailing die, means for positioning a heel with relation to said die, means operative in timed relation with said first-named means for effecting relative movement between the support and the nailing die to force together a heel and a heel seat of the shoe, and safety means responsive to the operation of said first-named means for insuring against operation of said second-named means when there is no heel in said first-named means.

29. In a heel attaching machine, a support for a shoe, a nailing die, a carrier unit which comprises fluid pressure operated mechanism for positioning and clamping a heel and which is movable between a heel loading position where the heel is presented to the unit and a heel attaching station where the heel is attached to the shoe, fluid pressure operated means for moving the carrier between its loading and its heel attaching positions, fluid pressure operated means for effecting relative movement between the support and the nailing die to force together the heel seat of the shoe and a heel delivered to the heel attaching station by the carrier unit, fluid pressure operated means cooperating with the nailing die to drive nails into the heel and the heel seat of the shoe whereby to attach the heel to the shoe, and means responsive to the operation of said fluid pressure operated mechanism for rendering said fluid pressure operated means inactive when there is no heel in the carrier unit thereby insuring against the operation of the machine through its cycle.

30. A jack for use in a machine which operates upon the rear ends of shoes and includes means for driving nails into a shoe part and into a heel seat of the shoe by a series of impacts, said jack comprising a post which is light in weight and is adapted to support a last carrying a shoe, a support for guiding the jack in a fixed path, and resilient means which is interposed between the support and said post and is adapted to allow the post and the work carried by it to yield under successive impact pressures applied to the last through the work.

31. In a machine for operating upon the heel portions

of shoes, a plunger mounted for movement in a rectilinear path, a jack post which is adapted to support a shoe on the last and is light in weight and is mounted on the plunger for movement therewith and is constrained for movement lengthwise of said path with relation to said plunger, a heavy spring interposed between the plunger and the jack post and adapted constantly to urge the jack post to a predetermined position on the plunger, and means for driving by successive impacts nails into the shoe part and into the heel seat of the shoe to attach said shoe part to the shoe, said jack post being movable lengthwise of said path against the action of said spring as successive impact pressures are applied against the work.

32. In a heel attaching machine, a nailing die having passages, a fixed but initially adjustable bearing post having a bore, a vertical piston rod which is mounted for reciprocation and constrained against rotation in the bore of said bearing post, and which has a bore in its upper end, a jack post having a spindle and having a shank fitting slidably in the bore at the upper end of the piston rod, means for insuring against rotation of the jack post on the piston rod, a strong spring interposed between the upper end of the piston rod and a shoulder of the jack, means for positioning a heel adjacent to the nailing die, means for operating the piston rod to force the heel seat of a shoe carried by a last mounted on the spindle of the jack post against the heel and the heel against the nailing die, drivers movable in the passage of the nailing die, and means for imparting to the drivers successive blows to cause nails in the passages of the nailing die to be driven into the heel and the heel seat of the shoe whereby to attach the heel to the shoe, said jack post during the attachment of the heel to the shoe having imparted to it vibratory movement with relation to the piston rod by reason of its being yieldingly supported on said rod by the spring.

33. In a heel attaching machine, a jack for a shoe, a nailing die having a plurality of passages, means for positioning a heel with relation to the nailing die, pneumatic pressure operated means for moving the jack toward the nailing die whereby to force the heel seat of the shoe against the heel and the heel against the nailing die, drivers movable respectively in the passages of the nailing die, means for delivering nails to the passages of said die, and means for applying successive impacts to the drivers simultaneously to cause them to drive said nails in the passages of the nailing die into the heel and the heel seat of the shoe whereby to attach the heel to the shoe.

34. In a machine for operating upon shoes, a support, a nailing die having a plurality of passages, means for effecting relative movement between the support and the nailing die to force two parts of a shoe together, drivers movable respectively between retracted and projected positions in the passages of the nailing die, and movable means comprising a gun for causing the drivers to be moved simultaneously in said passages toward their projected positions, said last-named means comprising mechanism, which is operative in response to movement of the gun to a predetermined position, for imparting to the drivers successive impacts whereby to cause them to drive nails in said passages into the shoe parts.

35. In a machine for operating upon shoes, a support, a nailing die having a plurality of passages, pneumatic pressure means for moving the support with relation to the nailing die to force two parts of a shoe together, drivers movable respectively between retracted and projected positions in the passages of the nailing die, movable means comprising a gun for causing the drivers to be moved toward their projected positions, said gun comprising mechanism operative as the gun is moved to impart to the drivers successive impacts simultaneously whereby to cause said drivers to insert nails in said passages into the shoe parts.

36. In a machine for operating upon shoes, a support,

a nailing die having passages, pneumatic pressure operated means for moving the support toward the nailing die to force two shoe parts together, a gun which is movable toward and away from the nailing die, a plurality of drivers movable between retracted and projected positions in the passages of said die, means associated with the gun for moving the drivers to and holding them in their retracted positions in the passages of the die, a hammer which is movable in the gun and engages the drivers, said drivers being movable into engagement with nails resting in the passages of the nailing die in response to initial movement of the gun toward said die, and means operative in response to further movement of the gun toward the nailing die for causing the hammer operating through the drivers to drive said nails with successive impact action into the heel and the heel seat of the shoe whereby to attach the heel to the shoe.

37. In a machine for operating upon shoes, a work support, a nailing die, means for moving the support toward the nailing die to cause two parts of a shoe to be clamped between the support and the die, and means cooperating with the nailing die for driving a plurality of nails simultaneously by successive impact action into the shoe parts to secured said parts together.

38. In a machine for operating upon shoes, a jack, a nailing die, means for effecting relative movement be-

tween the jack and the nailing die to clamp two parts of a shoe together, means cooperative with the nailing die for driving a plurality of nails simultaneously by successive impact action into the shoe parts to secure said parts together, and means which is associated with the support and is adapted to cause said shoe parts on the jack to yield to a slight extent away from the nailing die in response to force applied to them by nails as the result of successive nail driving impacts against said nails and which is adapted to cause the shoe parts to move back toward the nailing die between successive impacts.
